UNITED STATES PATENT OFFICE

CARL LADISCH, OF MEISSEN-ON-ELBE, GERMANY

SPRAYING NOZZLE

Application filed May 13, 1924. Serial No. 713,112.

My invention relates to a spraying nozzle or atomizer, and particularly to that type of spraying nozzle in which a compressed fluid such for example as compressed air or steam 5 is employed for spraying or atomizing a liquid of any consistency, and more particularly to heavy gelatinous liquids or solutions, and the like.

In carrying out the invention the compressed fluid is preferably delivered in the form of a swirling cone, and the liquid to be sprayed or atomized is so delivered that the swirling cone of compressed fluid completely or substantially envelopes and is in contact 10 with the liquid from the time and place of its delivery until it is completely sprayed or atomized. In carrying out the invention the apparatus made in accordance therewith, preferably includes a conical body member 15 and a liquid delivery pipe centrally disposed therewith so as to provide at the mouths or discharge orifices of these members an annular discharge passage for the fluid under pressure. The invention also contemplates 20 the provision of means for causing the fluid under pressure to assume a swirling conical form as emitted from the annular orifice, and in the preferred form of the invention the liquid discharge pipe is provided with a double 25 conical bore, whereby the liquid as discharged is engaged with and enveloped by the swirling cone of the compressed fluid to effect complete atomization of the liquid, as will be hereinafter more particularly described.

In the drawings Figure 1 is a central longitudinal section of a spraying nozzle made in accordance with my invention, and

Fig. 2 is a sectional plan taken through the 40 inlet supply connection for the compressed fluid.

Referring to the drawings, the spraying nozzle or atomizer therein illustrated, comprises a body member a , preferably in the 45 form of an inverted cone, and fitted at its larger end with a cap or cover a' . In a suitable position adjacent the larger end thereof, the body member a , is provided with an inlet connection b , for the supply of compressed air, steam or other similar fluid under pres-

sure. Inferiorly, the body member a , is fitted with a guide plate c , which directs the incoming compressed fluid so that the same is caused to travel in a circular path and to advance with an increasing velocity to the orifice of the body member at the smaller end thereof, it being noted that to assist this action the inlet connection is placed in a position which is substantially tangential to the larger end of the body member a . Within 55 the body member a , and concentric therewith, is a liquid discharge pipe e . This discharge pipe e , passes through the cap or cover a' , and in a suitable position is provided with an inlet connection f , for supplying the liquid 60 to be sprayed or atomized. The bore of the liquid pipe e , is double coned shape and the discharge orifice of the pipe e , is substantially in the same plane as the smaller end of the body member a , whereby there is provided an 65 annular discharge orifice d , between these parts of the spraying nozzle. By this structure the compressed fluid is discharged in the form of a double cone as indicated at d' and d'' , the vertex of each cone being indicated at d^* . Furthermore as indicated in the drawings, the effect of the double cone shaped bore 70 of the discharge is to sufficiently retard the rate of discharge of the liquid as to permit the liquid in leaving the orifice at the end of the outwardly tapering portion of the conical bore of the pipe e , to be entirely enveloped, and the surface portion thereof engaged by the swirling cone d' of the fluid under pressure, which as will be understood, assists materially in the complete atomization 75 of the liquid to be sprayed.

The bore at the outer end of the pipe e is 80 preferably fitted with a plunger g , controlled by a spring h , whereby the inner end of the plunger may be employed to clear the passage in the pipe e , and may also be set to regulate and control the passage of the liquid 85 through the same.

I claim as my invention:

1. In a spraying nozzle, a liquid supply pipe open at one end and having an unimpeded but restricted port appreciably distant from the open end thereof, the inner wall of the pipe flaring outwardly from the restrict- 100

- ed port to the end thereof to cause a liquid passing through the restricted port to flow slower along the flaring wall to the open end of the pipe, and a casing surrounding the said pipe and tapering to an open end substantially coincident with the open end of the said liquid supply pipe and forming therewith an annular discharge port for a fluid under pressure whereby the liquid flowing through the supply pipe in its substantial entirety is brought directly into contact with the fluid as the same is discharged through the said annular discharge port.
2. In a spraying nozzle, a liquid supply pipe open at one end and having an unimpeded but restricted port appreciably distant from the open end thereof, the inner wall of the pipe flaring outwardly from the restricted port to the end thereof to cause a liquid passing through the restrictive port to flow slower along the flaring wall to the open end of the pipe, a casing surrounding the said pipe and tapering to an open end substantially coincident with the open end of the said liquid supply pipe and forming therewith an annular discharge port, and means for admitting a fluid under pressure in a direction tangential to the inner tapering wall of the casing whereby through the inclination of the said wall and the tangential direction at which it is admitted the said fluid is discharged in the form of an inwardly directed swirling cone at the said annular discharge port whereby the liquid passing through the said liquid supply pipe in its substantial entirety is brought directly into contact with the fluid as the same is discharged from the said annular discharge port.
40. In testimony, that I claim the foregoing as my invention, I have signed my name this 24th day of April, 1924.

CARL LADISCH.
